(57) **CLAIM**

The ornamental design for buttons for a programmable robot, as shown and described.

DESCRIPTION

FIG. 1 is a top-left-isometric view of our buttons for a programmable robot including a body in phantom;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The features shown in dashed lines represent unclaimed portions of the buttons for the programmable robot and form no part of the claimed design.
